UNITED STATES PATENT OFFICE.

JOSEF MERZ, OF BRÜNN, AUSTRIA-HUNGARY.

EXTRACTION APPARATUS.

1,070,828.

Specification of Letters Patent.

Patented Aug. 19, 1913.

Application filed June 5, 1911. Serial No. 631,459.

To all whom it may concern:

Be it known that I, JOSEF MERZ, engineer, a subject of the Austro-Hungarian Emperor, and residing at Wannieckstrasse 12, Brünn, 5 Austria-Hungary, have invented Improvements in and Relating to Extraction Apparatus, of which the following is a specification.

The usual extraction apparatus operate 10 either only with solvents or only with vapors thereof.

The first method in which solvents are employed and which is principally used in connection with seeds and pulverulent materials 15 presents the defect that moist residuals are formed which require subsequent drying and this entails increased cost of construction and working expenses. The other process in which solvent vapors are employed 20 dry residuals are also formed but this process can only be adopted successfully in the case of bones and similar coarse grained porous moist materials and cannot be employed for the systematic extraction of pulverulent 25 materials.

The means for carrying these processes into practice present various constructional modifications according as they are intended 30 for use for extraction by means of solvents or for extraction by means of vapors.

For the extraction of most materials it is advantageous for the extraction to take place both by means of solvents and by means of vapors and this with the object 35 either of obtaining dry residuals or for increasing the yield. It is also advantageous in the case of materials which at high temperatures furnish liquefiable extracts to operate first of all with vapor in order to cause 40 the extractive substance to melt and then to lixiviate the extractive material with the solvent.

The present invention has for its object an apparatus which enables both processes to 45 be combined in any desired order. In accordance with the invention this result is attained by a reversing device which renders it possible to conduct the extraction agent from an evaporating chamber above or below 50 the material in the extraction chamber. In order to avoid losses of heat in the reversing device it is advantageous to arrange it in the extraction apparatus.

An embodiment of the invention is illustrated 55 in the accompanying drawing in which:

Figure 1 is a vertical section and Fig. 2 is a plan.

In the embodiment of the invention here illustrated the evaporating apparatus *a* is 60 combined with the extractor *b* to form a single vessel, the two being separated from each other by a partition *c*. In the extractor one or more upwardly directed pipes *d* are arranged; these pipes open at their lower 65 ends into the chamber *a* so that the vapors ascending therefrom are able to pass into the extractor over the material placed upon the sieve bottom *e*. Pipes *f* branch from the pipe *d* and open into the extractor over 70 the partition *c* and are adapted to conduct the vapors ascending from the evaporating chamber beneath the material. A reversing member *g* which is adapted to be operated from the exterior is mounted in the pipe *d* 75 and according to the position in which it is set it conducts the vapors ascending from the lower chamber *a* either over the material or through the pipes *f* beneath it. A cooling apparatus *i* which preferably acts 80 as a reflex cooler is provided beneath the cover of the apparatus. Said apparatus having an exit *l* cools and condenses the ascending vapors. The solvent may be introduced into the chamber *a* through any 85 suitable inlet, for example, as conventionally illustrated at *s* and the contents of said chamber may be withdrawn through an outlet *t*.

The operation of the apparatus is as follows: When the reversing member occupies the position in which the upper end of the pipe *d* is closed, the extraction is effected by means of the vapors of the solvent which flow through the material from below; this 90 is the vapor extraction process. If the reversing member is reversed the vapors ascending from the chamber *a* pass through the pipe *d* into the extraction chamber and are condensed by the cooling apparatus arranged 95 beneath the cover so that they penetrate the material in liquid form; this is the liquid extraction process. When it is desired to obtain a dry residue when dealing with fine grained or pulverulent materials 100 the liquid extraction operation is effected in the known manner in the first place and when this operation is completed the vapors of the solvent are conducted downward and through the material by reversing the valve 105 *g* from the exterior. These vapors which can if necessary be heated by a heating 110

coil λ located over the partition or at any other part of their path are forced through the mass until it is freed from moisture.

Having now particularly described and ascertained the nature of my said invention and in what manner the same is to be performed, I declare that what I claim is:

1. An extraction apparatus of the character described comprising a casing having its interior divided into an evaporating chamber and an extraction chamber, a conduit connecting said chambers and arranged entirely within the casing, and means operable from outside the casing for causing vapor conducted from the evaporating chamber to the extraction chamber to enter the latter above or below the material to be treated therein, as desired.

2. An extraction apparatus of the character described comprising a casing having its interior divided into an evaporating chamber and an extraction chamber, means for conducting vapor from the evaporating chamber to the extraction chamber, a cooling device for condensing such vapor in the extraction chamber, and adjustable means within the extraction chamber for directing said vapors against the cooling device or beneath the material in the extraction chamber.

3. An extraction apparatus of the character described comprising a casing having its interior divided into an evaporating

chamber and an extraction chamber, a conduit connecting said chambers and arranged entirely within the casing, said conduit having two outlets one adjacent the upper end of the extraction chamber and the other below the support for material to be treated within such chamber, a cooling device with in the upper portion of the extraction chamber, and means operable from outside the casing for controlling the passage of vapors through both outlets of the conduit.

4. An extraction apparatus of the character described comprising a casing having its interior divided into an evaporating chamber and an extraction chamber, a perforated support for material to be treated within the extraction chamber, a conduit for conducting vapor from the evaporating chamber to the extracting chamber having two outlets one adapted to introduce the vapor passing therethrough beneath said perforated support, means for condensing vapor passing through the other outlet from the conduit, and a heater arranged in the extraction chamber beneath the perforated support therein.

In testimony whereof I affix my signature in presence of two witnesses.

JOSEF MERZ.
